MACHINE FOR BONDING AND DEBONDING
BRAKE SHOE LININGS

Jennings B. Williams, Tulsa, Okla.

Application April 4, 1952, Serial No. 280,487

14 Claims. (Cl. 219—19)

1

This invention relates to a machine and method for bonding and de-bonding linings to brake shoes.

More particularly, the invention relates to electrical means for heating the lining of a brake shoe, whereby to cause the shoe to adhere thereto, the shoe and lining being tightly pressed together.

One important object of the invention is to provide a novel machine of the above character, the parts of which may be assembled in the field so that the machine may be transported in disassembled condition.

Another important object of the invention is to provide a machine having means insuring uniform pressure between the brake shoe and lining while undergoing bonding.

A further object of the invention is to provide a machine of this description having a novel arrangement of supporting members for holding a brake shoe and lining ready for bonding.

A still further object of the invention is to provide, in a machine of this character, a novel arrangement of an electrical contact member for engaging the brake shoe during bonding and de-bonding.

A still further object of the invention is to provide means for insuring proper action of a hydraulic pressing device in such manner as to force the shoe and lining together at substantially uniform pressure.

Yet another object of the invention is to provide means whereby brake shoes and lining of different widths may be assembled for action by the machine.

Again, it is an object of the invention to provide an improved process for bonding and de-bonding brake shoes and linings.

With the above and other objects in view, as will be hereinafter described, the invention consists in general of the novel method set forth and of certain novel details of construction and combinations of parts hereinafter fully described, illustrated in the accompanying drawings, and particularly pointed out in the claims.

In the drawings:

Figure 1 is a side elevation of the improved machine, the view being partly in section,

Figure 2 is an end elevation of the machine as shown in Figure 1,

Figure 3 is an enlarged fragmentary section on line 3—3 of Figure 1,

Figure 4 is a section on line 4—4 of Figure 1,

Figure 5 is a perspective view showing a pair of the contact members, their mounting and the bus bar leads,

2

Figure 6 is a perspective view showing the electrical circuit means and the circuit closure used in this invention,

Figure 7 is a greatly enlarged view on line 7—7 of Figure 1,

Figure 8 is an enlarged view on line 8—8 of Figure 1,

Figure 9 is a fragmentary top plan view of one of the molds showing the positioning means for a brake shoe, and

Figure 10 is a detail sectional view showing a part of a mold, a liner therein, the shoe engaged with the liner, and the contact members or brushes engaged with the shoe and illustrating by dotted lines the directional flow of current through the shoe.

In the form of the invention illustrated in the accompanying drawings, there is illustrated a bottom frame of rectangular form and having long members 10 and short members 11 preferably of angle iron and welded together at their ends. At each corner of the frame, there is provided a tubular guide post 12 and on top of these posts is fitted a cap 13 to which the upper ends of posts 12 are secured by means of Allen screws 14. The upper ends of the posts 12 are threaded as shown in Figure 1 and carry adjusting nuts 15. From the corners of the bottom frame extend diagonal members 16 which support a hydraulic cylinder 17 located centrally of the bottom frame. This cylinder may be supplied with fluid from any desired source through the valved pipe 18 and, when desired to relieve the pressure on the cylinder, the fluid may be drawn off through the exhaust pipe 19, which is also a valved pipe. Fitted in the cylinder 17 is a plunger 20 which carries on its upper end a rectangular platform 21, provided with an upstanding peripheral flange 22. Within this flange is located a series of individually movable plates 23^a on each of which is mounted a mold 23. Extending upwardly from the platform are supporting bars 24 and the upper ends of these bars are fixedly attached to a flat frame 25 which surrounds the upper parts of the molds 23 and is provided at each corner with an opening 26 so that the flat frame 25 is slidably fitted on the posts 12. An angle iron post bracing frame 25^a has the ends of its members securely welded to the posts 12 about midway of their heights.

Each of the molds 23 is arranged to carry a brake shoe and its lining. To this end the upper edge of each mold is provided with a semi-circular notch 27, the central part of which is recessed as at 28 so that a pair of side flanges 29 is arranged on the mold in order that a brake

shoe and liner may be fitted in the recess. On these flanges 27 are mounted sliding guides 30 for adjustment closely to the proper widths of the brake shoe and liner received in this mold. Also, peripheral stops 31 are provided for close adjustment for diameters.

The plates 23^a are independently movable with respect to each other and in order to insure that each mold receives the proper pressure from the platform 24, this platform is provided underneath each plate with a series of spring seats 32 and springs 33 are fitted in these seats and bear against the underside of the respective plate. This arrangement provides, as shown in Figure 10, for the proper location of a brake shoe 35 and a liner 34.

Fitted on the posts 12 is a head 36 having openings 37 receiving the posts 12. Between the nuts 15 and the head 36 are springs 38 which urge the head downwardly. On each of the posts is fitted a collar 39 which is secured in proper position on the post by an Allen screw 40. These collars effectually limit the downward movement of the head 36, while the springs 38 permit a resisted upward movement of the head. Secured to the head in vertical alignment above the respective molds are insulating blocks 41 and beneath these blocks are fixed heat insulating blocks 41^a. Fixed to each of the blocks 41^a and extending transversely of the machine is a pair of members 42 each forming a tube provided with inturned flanges 43 having their inner edges spaced. The tubes 42 are thus electrically insulated from the head 36 by the blocks 41 and the latter are protected from the heat produced during the bonding and de-bonding operations. These members 42 may be termed contact holders and each member carries a semi-circular contact member or brush 44, which extends through the opening between the flanges 43 at its upper edge and is there provided with lateral flanges 45 so as to form a T-shaped structure for holding the contact 44 in position on the head 36. The body of each contact member 44 is semi-circular in elevation to correspond with the shape and size of the brake shoe. Extending from each of the members 44 is a conductive lead 46 and these leads are secured to bus bars 47 supported from the head 36 by means of brackets 48, insulation 49 being provided between the brackets and bus bars. Mounted on the cap 13 is a solenoid controlled switch 50. One of the bus bars 47 receives direct current from a suitable source through a conductor 51, while the other bus bar is connected by a conductor 52 with one terminus of the switch (not shown). The other terminus of the switch is connected to the source of direct current through a conductor 53. Also fixed to the cap 13 is a micrometric switch 54 connected by conductors 55 to the solenoid controlled switch 50 and receiving suitable alternating current through conductors 56. The switch 54 is of the plunger or push button type and mounted on the head 36 is a bracket 57 carrying an adjustable finger 58 aligned with the switch 54, the adjustment being such that when the head 36 rises to a certain extent the switch 54 will close, the solenoid in the switch 50 will be energized and current will flow from each of the bus bars to a respective contact member 44.

To operate the device it is desirable to use a motor driven high output field controlled D. C. generator G. The reason for using the output controlled generator is that one can use higher

amperage in the de-bonding process than is used in the bonding operation. As mentioned before, the generator is of the high ampere, low voltage field controlled D. C. type. The negative lead 5 from the generator is bolted directly to the main negative brush bus bar. The positive lead from the generator is bolted to one side of the current control switch, which is opened and closed by means of a micro-switch operated solenoid. A short wire runs from the other terminal of the control switch to the positive main brush bus bar. The amperage is controlled by means of resistance in the generator field circuit.

In the operation of the circuit, the generator is set for the desired output, then the bonding machine is loaded, and the ram press is raised. The brake shoes in the die blocks contact the carbon brushes, which are in effect carbon resistance heating electrical contacts, and the ram press continues its upward movement, raising the head plate until all brushes or contacts and brake shoes have the desired amount of pressure on them. The micro-switch is then actuated by means of the actuating finger, which in turn energizes the solenoid. The solenoid actuates the direct current switch, allowing current to flow to all brushes. At this instant, upward movement of the ram press is controlled by means of the adjustable stops shown. When the desired amount of heat has been obtained on brake shoes the ram press is lowered. When the head plate drops a few thousandths of an inch, the micro-switch again actuates, causing the solenoid to open the direct current control switch before all the pressure is off the brushes, preventing any chances of an arc occurring.

In order to limit the upward movement of the platform 23, there is fitted on each of the posts a collar 59 secured in desired position by Allen set-screws 60.

In beginning the operation of the machine, liners are placed in the molds and the brake shoes are fitted inside of these liners. Fluid is then introduced through the pipe 18 into the cylinder 17. This will cause the plunger and the platform 21 to rise and the contact members, as shown in Figure 10, will engage against the brake shoe 35 adjacent each edge thereof. As the platform 21 moves toward the upper level of its movement, the contacts 44 will be engaged by the molds and raise the head 36. As the head 36 rises, the finger 58 will operate the switch 54 and, as before stated, the contacts 44 will become the spaced terminals of an open circuit, which will close, as shown in Figure 10, through the brake shoe. The consequence will be that the brake shoe will reach such a temperature that the pressure from the cylinder will cause bonding or de-bonding of the shoe 35 and liner 34 in accordance with the amperage used.

It is obvious that the temperature to which the liner 35 is raised may be regulated in any suitable way so that the proper bonding or de-bonding temperature may be attained as desired by the operator.

From the above detailed description of the invention, it is believed that the construction, use, and operation thereof will at once be apparent, and while there is herein shown and described the preferred embodiment of the invention, it is nevertheless to be understood that minor changes may be made therein without departing from the spirit and scope of the invention as claimed.

What is claimed as new, is:

1. In a bonding machine of the class described, a frame, a platform mounted on said frame for vertically guided movement, hydraulic means for moving said platform, mold supporting plates carried by said platform, molds carried by said plates, and pairs of spaced electrical contact members supported within the frame in vertical alignment with respective molds.

2. In a bonding machine of the class described, a frame, a platform mounted on said frame for vertically guided movement, hydraulic means for moving said platform, mold supporting plates carried by said platform, molds carried by said plates, each of said molds having a semi-circular notch in its upper edge, said notch being recessed to form a channel throughout its length, and pairs of spaced electrical contact members supported within the frame in vertical alignment with respective molds.

3. In a bonding machine of the class described, a frame, a platform mounted on said frame for vertically guided movement, hydraulic means for moving said platform, mold supporting plates carried by said platform, molds carried by said plates, springs arranged in sets and spaced uniformly between the mold supports and platform, and pairs of spaced electrical contact members supported within the frame in vertical alignment with respective molds.

4. In a bonding machine of the class described, a frame, a platform mounted on said frame for vertically guided movement, hydraulic means for moving said platform, mold supporting plates carried by said platform, molds carried by said plates, each of said molds having a semi-circular notch in its upper edge, said notch being recessed to form a channel throughout its length, springs arranged in sets and spaced uniformly between the mold supports and platform, and pairs of spaced electrical contact members supported within the frame in vertical alignment with respective molds.

5. In a bonding machine of the kind described, a frame, a platform mounted on said frame for vertically guided movement, hydraulic means for moving said platform, mold supporting plates carried by said platform, molds carried by said plates, pairs of spaced electrical contact members aligned above said molds, and carrier means supporting said contact members for vertical movement on the frame.

6. In a bonding machine of the kind described, a frame, a platform mounted on said frame for vertically guided movement, hydraulic means for moving said platform, mold supporting plates carried by said platform, molds carried by said plates, pairs of spaced electrical contact members aligned above said molds, carrier means supporting said contact members for vertical movement on the frame, and stop means on said frame limiting downward movement of said last named means.

7. In a bonding machine of the kind described, a frame, a platform mounted on said frame for vertically guided movement, hydraulic means for moving said platform, mold supporting plates carried by said platform, molds carried by said plates, pairs of spaced electrical contact members aligned above said molds, carrier means supporting said contact members for vertical movement on the frame, stop means on said frame limiting downward movement of the carrier means, and springs yieldably holding said carrier means against said stop means.

8. In a bonding machine of the kind described, a frame, a platform mounted on said frame for vertically guided movement, hydraulic means for moving said platform, mold supporting plates carried by said platform, molds carried by said plates, pairs of spaced contact members aligned above said molds, carrier means supporting said contact members for vertical movement on the frame, circuit connections for said contact members, and switch means for said circuit connections opened and closed as the carrier means moves upwardly and downwardly.

9. In a bonding machine of the kind described, a frame, a platform mounted on said frame for vertically guided movement, hydraulic means for moving said platform, mold supporting plates carried by said platform, molds carried by said plates, pairs of spaced contact members aligned above said molds, carrier means supporting said contact members for vertical movement on the frame, stop means on said frame limiting downward movement of said last named means, circuit connections for said contact members, and switch means for said circuit connections opened and closed as the carrier means moves upwardly and downwardly.

10. In a bonding machine of the kind described, a frame, a platform mounted on said frame for vertically guided movement, hydraulic means for moving said platform, mold supporting plates carried by said platform, molds carried by said plates, pairs of spaced contact members aligned above said molds, carrier means supporting said contact members for vertical movement on the frame, stop means in said frame limiting downward movement of the carrier means, springs yieldably holding said carrier means against said stop means, circuit connections for said contact members, and switch means for said circuit connections opened and closed as the carrier means moves upwardly and downwardly.

11. In a bonding machine of the class described, a frame, a platform mounted on said frame for vertically guided movement, hydraulic means for moving said platform, mold supporting plates carried by said platform, molds carried by said plates, pairs of spaced contact members aligned above said molds, carrier means supporting said contact members for vertical movement on the frame, stop means on said frame limiting downward movement of the carrier means, springs yieldably holding said carrier means against said stop means, means for adjusting the tension of said springs, circuit connections for said contact members, and switch means for said circuit connections opened and closed as the carrier means moves upwardly and downwardly.

12. In a bonding machine of the class described, a frame, a platform mounted on said frame for vertically guided movement, hydraulic means for moving said platform, mold supporting plates carried by said platform, molds carried by said plates, each of said molds having a semi-circular notch in its upper edge, said notch being recessed to form a channel throughout its length, pairs of spaced contact members aligned above said molds, carrier means supporting said contact members for vertical movement on the frame, stop means on said frame limiting downward movement of the carrier means, springs yieldably holding said carrier means against said stop means, circuit connections for said contact members, and switch means for said circuit connections opened and closed as the carrier means moves upwardly and downwardly.

13. In a bonding machine of the class described, a frame, a platform mounted on said frame for vertically guided movement, hydraulic means for moving said platform, mold supporting plates carried by said platform, molds carried by said plates, springs arranged in sets and spaced uniformly between the supporting plates and platform, pairs of spaced contact members aligned above said molds, carrier means supporting said contact members for vertical movement on the frame, stop means on said frame limiting downward movement of the carrier means, springs yieldably holding said carrier means against said stop means, means for adjusting the tension of said springs, circuit connections for said contact members, and switch means for said circuit connections opened and closed as the carrier means moves upwardly and downwardly.

means above upward and downward, 20
14. In a bonding machine of the class described, a frame, a platform mounted on said frame for vertically guided movement, hydraulic means for moving said platform, mold supporting plates carried by said platform, molds carried by said plates, each of said molds having a semi-circular notch in its upper edge, said notch being recessed to form a channel throughout its length, springs arranged in sets and spaced uniformly between the supporting plates and platform, pairs of spaced contact members aligned above said molds, 25

carrier means supporting said contact members for vertical movement on the frame, stop means on said frame limiting downward movement of the carrier means, springs yieldably holding said carrier means against said stop means, means for adjusting the tension of the last springs, circuit connections for said contact members, and switch means for said circuit connections opened and closed as the carrier means moves upwardly and downwardly.
